UNITED STATES PATENT OFFICE.

STEWART BROWN, OF CHICAGO, ILLINOIS, ASSIGNOR OF ONE-HALF TO HARLAND K. DELAHANTY, OF CHICAGO, ILLINOIS.

TOY PISTOL.

Application filed November 8, 1924. Serial No. 748,737.

This invention relates to a toy pistol and has for its primary object the construction and association of parts whereby the cost of manufacture will be greatly reduced without in any way sacrificing the novelty of the toy.

Another object of my invention is the novel manner of associating the parts so that the missile may be quickly arranged in place and press the coil spring to an extent great enough to have the required amount of power to forcibly throw the missile from the rod.

Besides the above my invention is distinguished in the novel way of supporting and projecting the missile in combination with the novel construction of trigger.

Another object of my invention is the design of a novel form of target structure to be used with my improved toy pistol.

With these and other objects in view the invention will be better understood from the following detailed description taken in connection with the accompanying drawing

25 wherein:

Fig. 1 is a side elevation of my improved toy pistol.

Fig. 2 is a longitudinal sectional view.

Fig. 3 is a cross sectional view on the line 30 3—3 of Fig. 1.

Fig. 4 is a cross sectional view on the line 4—4 of Fig. 1.

Fig. 5 is a perspective view of a target structure to be used with my improved

35 pistol.

Fig. 6 is a top plan view.

Fig. 7 is a sectional view on the line 7—7 of Fig. 6.

Fig. 8 is a perspective view of one of the 40 movable targets.

Again referring to the drawing illustrating one of the many constructions of my invention the numeral 1 designates a two part casing having a hollow handle extension 2.

45 The two parts forming the casing are secured together by fasteners 3 which may be of any number and arranged in any position found advantageous. This casing is formed with two holes 4 and 5 and with an outlet 6.

50 The missile supporting and projecting mechanism consists of a rod 7 that projects through the outlet 6 and has its inner end formed

into a laterally extending arm 8 that terminates in a loop 9 engaging one of the fasteners 3. The trigger 10 is formed from a strip of metal bent to have an angle arm 11 formed with a hole 12 slidably receiving the rod 7. The remaining end portion of the strip is formed into a hook 13 while the intermediate portion is bent into a finger 60 piece 14 projecting through the slot 4.

The missile 15, in this particular instance, is formed of wood provided with the through bore 16 that slidably receives the rod 7. A coil spring 17 is mounted on the rod with one end abutting the arm 11 and the other end arranged to engage the missile so that in the sliding of the missile on the rod the spring will be compressed to have the proper power when the missile is confined behind the hook 13. To complete the device I provide a cord 18 having one end connected to the missile and the other end to one of the fasteners 3.

70 From the foregoing description taken in connection with the accompanying drawing it will be seen that I provide an inexpensive toy pistol having the required amount of power and in which the parts are so constructed and arranged that the spring 17 may be properly compressed by the placing 80 of the missile on the rod 7 and the construction of the trigger and arrangement being such that the missile may be quickly released.

75 My improved target structure comprises a front wall 19 and a rear wall 20 attached to the front wall by the wire connector 21 of a construction that the front wall may be folded parallel to the back wall for shipping purposes. The front wall may have printed thereon any suitable design and a stationary target 22 is arranged thereon. The rear wall is provided with a horizontal flange 23 and this flange is provided with a series of slots 24 extending part way into the vertical portion of the rear wall. Movable targets 25 have clips 26 bent into the slots so as to have swinging movement and each movable target comprises a head portion 27 and body portion 28 carrying a number 29.

100 It is, of course, to be understood this target may be constructed in various other manners than illustrated without departing from the spirit of this invention, therefore, I do

not desire to be limited in any manner except as set forth in the claims hereunto appended.

Having thus described my invention what 5 I claim is:

1. A toy of the class described including a casing having a handle extension, a missile supporting member mounted in the casing and having an end portion projecting therefrom, a missile adapted to be mounted on the member, means for projecting and discharging the missile from the member, and a releasing member for the missile, said releasing member defining an end portion engaging the missile and an opposite end portion defining a loop slidably received by the supporting member.
2. A toy of the class described including a missile supporting member, a releasing member having an end portion defining a hook and an opposite end portion defining a loop slidably received by the supporting member, a missile adapted to be mounted on the supporting member and adapted for releasable engagement with the end portion of the releasing member defining a hook, and resilient means embracing the supporting member and adapted to be compressed by the missile when mounted on the supporting member in engagement with the hook, said resilient means when compressed by the missile having an end portion in abutment with the missile and an opposite end portion in abutment with the loop.
3. A toy of the class described including a missile supporting member, a releasing member having an end portion defining a hook and an opposite end portion defining a loop slidably received by the supporting member, said releasing member having a portion defining a finger piece permitting operation of the releasing member, a missile adapted to be mounted on the supporting member and adapted for releasable engagement with the end portion of the releasing member defining a hook, and resilient means embracing the supporting member and adapted to be compressed by the missile when mounted on the supporting member in engagement with the hook, said resilient means when compressed by the missile having an end portion in abutment with the missile and an opposite end portion in abutment with the loop.
4. A toy pistol including a missile supporting member, a releasing member having an end portion defining a hook and having a portion providing a finger piece permitting operation of the releasing member and having an opposite end portion slidably connected to the supporting member, a missile adapted to be mounted on the supporting member for engagement with the hook, means disposed between the missile and the said opposite end of the releasing member

for projecting and discharging the missile from the supporting member when the hook is moved from engagement with the missile.

5. A toy pistol comprising a hollow casing having a hollow handle extension, a rod mounted within the casing with one end pivoted thereto and its other end portion projecting out of the casing, a trigger loosely mounted on the rod and having a portion projecting beyond the casing, a compressible spring mounted on the rod, and a missile adapted to be mounted on the rod for compressing said spring and held in such position by said trigger.

6. A toy pistol comprising a two part casing, fasteners for connecting the parts of the casing together, one end of said casing provided with an outlet, a rod projecting through the outlet and having its inner end formed with a lateral arm pivoted to one of said fasteners, a coil spring on the rod, and a trigger in the form of a metal strip bent to have one end slidably connected to the rod and abutting said arm, its intermediate portion formed into a finger piece, and its other end formed into a hook, a missile having a bore for slidably receiving said rod and adapted to compress said spring and be confined behind said hook, and a cord having one end connected to the missile 95 and the other end to said casing.

7. A toy pistol including a casing having an extension providing a handle portion and having spaced slots formed therein and provided with an outlet, a missile supporting member having an end portion confined in the casing and pivotally connected thereto and an opposite end portion projecting through the outlet from the casing, a releasing member including an end portion projecting through one of the slots and defining a hook and an opposite end portion slidably received by the supporting member and having a portion bent to provide a finger piece extending through the other of the slots, a 110 missile adapted to be mounted on the supporting member for engagement with the hook, and a spring member embracing the supporting member and adapted to be compressed by the missile when mounted on the 115 supporting member for engagement with the hook, said spring member when compressing by the missile having an end portion in abutment with the missile and an opposite end portion in abutment with the missile and an opposite end portion of the releasing member.

8. A toy pistol including a missile supporting member, a missile adapted to be carried by the supporting member and to be projected therefrom, means for holding the 125 missile against projection from the supporting member, and means for projecting the missile when free from engagement with the holding means, said projecting means having engagement with the holding means 130

for holding the holding means in holding relation with the missile.

9. A toy pistol including a missile supporting member, a missile adapted to be mounted on the supporting member and projecting therefrom, a releasing member having an end portion in hooked relation with the missile and having an opposite end portion operatively connected to the supporting

member, and means for projecting the missile when free from engagement with the releasing member, said means including an end portion in engagement with the said opposite end of the releasing member for yieldably holding the releasing member in hooked engagement with the missile. 10 15

In testimony whereof I affix my signature.
STEWART BROWN.
